(57) **CLAIM**

We claim the ornamental design for a crimping tool, as shown and described.

DESCRIPTION

FIG. 1 is a top perspective view of our design;

FIG. 2 is a bottom perspective view of our design;

FIG. 3 is a front view of our design;

FIG. 4 is a rear view of our design;

FIG. 5 is a left view of our design;

FIG. 6 is a right view of our design;

FIG. 7 is a top view of our design; and,

FIG. 8 is a bottom view of our design.

The features shown in dashed lines in the drawings depict portions of the crimping tool that form no part of the claimed design.
